UNITED STATES PATENT OFFICE.

WILLIAM S. FOSTER, OF DALLAS, WISCONSIN.

ROAD-PLANER.

1,107,279.

Specification of Letters Patent. Patented Aug. 18, 1914.

Application filed November 6, 1913. Serial No. 799,431.

To all whom it may concern:

Be it known that I, WILLIAM S. FOSTER, a citizen of the United States, residing at Dallas, in the county of Barron and State 5 of Wisconsin, have invented a new and useful Improvement in Road-Planers, of which the following is a specification.

The primary object of this invention is the production of a road finishing device, 10 which is particularly adapted to plane off transverse ridges in roads rendering the surface of the road plane.

A further object is the production of a device of said character, which is free from 15 side draft whereby the device will travel in a direct line parallel to its longitudinal sides and smooth the surface of the road in a plane.

To these ends my invention comprises the 20 following features of construction and combination of parts which are simple, inexpensive and effective in operation.

In the accompanying drawing forming part of this specification, Figure 1 is a plan 25 of my invention; Fig. 2 is a side elevation partly in section; Fig. 3 is a section taken on the line $\alpha-\alpha$ of Fig. 1; Fig. 4 is a perspective of one of the shoes employed for raising the forward end of the device when 30 it is idle and being drawn from one place to another for operation, and Fig. 5 is a side elevation of a detail of one of the runners showing one of the shoes applied thereto.

Roads usually wear into a form having 35 transverse ridges. Various devices have been designed in attempting to level such roads and smooth their surfaces, but these devices have not accomplished the results for which they have been designed, owing 40 to the construction of the parts, the position in which the cutters or scrapers are held and the side draft produced by the scraping elements upon the device. These objections I overcome by certain improvements, one 45 construction of which is illustrated by the accompanying drawing, in which—

A and B represent two long runners, said 50 runners as shown being held spaced apart in parallel relation by the cross pieces or stays 2. Each of these runners consists of a bar of wood or other suitable material 3, longitudinally disposed throughout substantially the entire length of the runner and tapered downwardly by slanting one side 4 of 55 each bar, which is placed on the outer side of the device, inwardly. To the two opposite

sides of each bar are secured such as by bolts 5, a pair of blades 6, made of metal or other suitable material, the lower edges of which project below the lower edge of the bar 3 and have clamped between them a narrow metal runner blade 7, which is shown sharpened on its lower edge. The method of securing said runner blade between said edges is by means of bolts 8 or other suitable means. The runner blades 7 on the side bars or runners of the device are adapted to travel in longitudinal grooves made in the road by cutters formed by down turned noses 9 formed on the forward ends of the runner blades. These cutters form grooves or furrows in the road while the planer device is being drawn ahead either by horses or other motive power. As illustrated suitable draft mechanism C is attached to the forward ends of the runners to which horses may be hitched to propel the device when in use. The runners may be of any suitable construction so long as they have forward furrow or groove forming means and their lower edges adapted to follow in grooves produced thereby.

Near the forward end of the runners and secured between them is a suitable harrow device such as D consisting of, a plank 10 which is secured to the adjacent inner faces of the runners by brackets 11, and harrow teeth such as 12 passing downwardly through the plank and held rigidly in position. Immediately back of the harrow device and secured to the inner adjacent faces of the runners is a planing tool such as E consisting of a bar 13 disposed transversely at an oblique angle between the runners, the method of attachment to the runners being 95 by means such as brackets 14. To the lower forward face of this bar is secured a cutting blade 15 such as by bolts 16. The lower cutting edge of the cutting blade 15 and the lower points of the harrow teeth 12 lie in substantially the same horizontal plane with the lower edges of the runners 7. Said teeth and blade thereby engage the ground owing to the runners 7 traveling in the grooves or furrows cut by the nose points 9 on the forward ends of the runner blades. The runner blades engaging the surface of the ground in the grooves cut by the nose pieces hold the runners against lateral movement while the device is being drawn ahead and 105 subjected to any side draft caused by uneven contact of the harrow teeth and planing tool

with ridges. The harrow teeth break up the ridges so that the planing tool will cut the ground smoothly and drag all loose earth forward filling any depressions and leveling the surface in an even plane. The long runners coating with the harrow and planer elements also assist in producing said result.

5 The operator may assist in guiding the device when turning around by the use of handles 16 or he may be seated on the device 10 on a seat 17 placed near the rear end of the runners.

15 When it is desired to draw the device over an obstruction or when not in use for leveling a road the forward ends of the runners may be placed upon similar shoes such as F, one shoe being provided for each runner. The shoe illustrated for this purpose consists of a body 18 having a downwardly and rearwardly curved forward end 19, which is 20 adapted to guide over the ground. The forward portion of the shoe has a strap 20 through which the nose 9 may be inserted and held and a pair of side lugs 21 disposed 25 near the rear end of the shoe, which are adapted to engage with the lower edge of the forward portion of the runner blade to prevent lateral movement. A shoe of this construction may easily be adjusted to the nose 30 end of the runner blade or removed therefrom when it is desired to operate the road planer to level the surface of a road.

35 This invention contemplates the use of any road trimmer such as a cutting, leveling and finishing tool in combination with the runners which are disclosed and various modifications may therefore be designed within the spirit of this invention.

40 In operation the device is drawn ahead over the road to be trimmed and finished. The cutting noses groove the surface of the road and the planer blades follow in the grooves and engage the device with the surface of the road to prevent any lateral movement or side draft of the device. While the 45 device is moving ahead the trimming elements plane and finish the surface substantially in a plane. After the device is used and it is desired to move to a new place for 50 operation, the shoes are adjusted over the nose ends of the runner blades.

In accordance with the patent statutes I have described the principles of operation of my invention together with the apparatus

which I now consider to represent the best 55 embodiment thereof but I desire to have it understood that the construction shown is only illustrative and that the invention can be carried out by other means and applied to uses other than those above set forth within 60 the scope of the following claims.

Having described my invention, what I claim as new and desire to protect by Letters Patent is:—

1. A road planer, comprising, in combination, a plurality of long parallel runners held evenly spaced apart having forward depending groove cutters and lower thin edges adapted to follow in the grooves produced by said cutters and prevent lateral movement 70 of said runners and an earth working tool carried between said runners for trimming and finishing the surface of a road substantially in a plane.

2. A road planer, comprising, in combination, a plurality of long parallel runners held evenly spaced apart having forward depending cutters adapted to groove the surface of a road and lower thin edges adapted to follow in the grooves produced by said 80 cutters and prevent lateral movement of said runners, a harrow element carried between said runners near the forward end of the device and a tool carried between said runners following said harrow element for 85 trimming and scraping the surface of the road and finishing it substantially in a plane.

3. A road planer, comprising, in combination, a plurality of long parallel runners held spaced apart having forward depending cutters adapted to groove the surface of a road, said runners being adapted to follow in the grooves made by said cutters, an earth working device carried between said 95 runners for trimming and finishing the surface of the road substantially in a plane and shoes detachably secured over the forward ends of said runners adapted to carry the forward ends of said runners with said cutters out of contact with the ground.

In testimony whereof, I have signed my name to this specification, in the presence of two subscribing witnesses.

WILLIAM S. FOSTER.
